United States Patent Office.

HARRISON PARKER AND JONATHAN C. SLEEPER, OF BOSTON, MASSACHUSETTS.

Design No. 2,945, dated March 3, 1868.

DESIGN FOR A TRADE-MARK.

The Schedule referred to in these Letters Patent and making part of the same.

TO ALL PERSONS TO WHOM THESE PRESENTS MAY COME:

Be it known that we, HARRISON PARKER and JONATHAN C. SLEEPER, of Boston, in the county of Suffolk, and State of Massachusetts, have invented or produced a new and ornamental Design for a Trade-Mark; and we do hereby declare the same to be fully described in the following specification, and represented in the accompanying drawing.

It consists of a shield, with a double border, a a, having at its corners four circles or circular shields, b, each of which is crossed by a series of arrows, c. Between the said circles, and at each of the sides and ends of the main shield, is a row of circles, as shown at d.

We claim as our invention—

The design for a trade-mark, as herein described, and as represented in the accompanying drawing.

HARRISON PARKER,
JONATHAN C. SLEEPER.
